(57) **CLAIM**

We claim the ornamental design for a table, as shown and described.

DESCRIPTION

FIG. 1 is a front perspective view of a table; FIG. 2 is a bottom perspective view of a table of FIG. 1; FIG. 3 is a rear perspective view of a table of FIG. 1; FIG. 4 is a right side view of a table of FIG. 1, the left side view is a mirror image of the right side view of FIG. 4; FIG. 5 is a top view of a table of FIG. 1; and, FIG. 6 is a bottom view of a table of FIG. 1.

The dashed lines and broken lines are for purposes of illustrating environmental structure and form no part of the claimed design. The table is shown with a symbolic break in its length and height. The appearance of any portion of the article between the break lines forms no part of the claimed design.
